(57) **CLAIM**

The ornamental design for a storage cabinet for bottles, as shown and described.

DESCRIPTION

FIG. 1 is a perspective view showing the front, top, and right side of a storage cabinet for bottles which forms my new design;

FIG. 2 is a front elevation thereof, the broken lines showing a pair of bottles being for illustrative purposes only and forming no part of my design;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a cross section thereof taken along lines 8—8 of FIG. 2.
